DEMODULATING CIRCUIT ARRANGEMENT

August Karolus, Leipzig, Germany, assignor to
Radio Corporation of America, a corporation
of Delaware

Application November 30, 1928, Serial No.
322,754, and in Germany December 12, 1927

1 Claim. (Cl. 250—21)

This invention relates to the demodulation of modulated alternating current or, in other words, its purpose is to separate the modulating frequencies from the modulated or carrier frequency 5 or wave. The application of the invention in connection with picture telegraphy work brings out the essential features of the invention with particular clearness for which reason its use for picture telegraphy shall here be especially considered.

For the purpose of insuring undistorted amplification of the frequencies produced in exploring a picture and occupying a wide frequency band, the so called carrier wave method has heretofore 15 been used in picture transmission by telegraphy, in other words, the picture signals are amplified and transmitted in the form of modulations of a separately generated carrier wave. For instance, in picture transmitter equipments operating with picture exploration by optical or luminous means, this is effected by that the light brought to act upon the photoelectric cell is periodically interrupted, whereby the carrier frequency is obtained. The modulation of this carrier frequency obtained by the interruption of light by means of the frequencies resulting from the distribution of brighter and darker spots in the picture in this case is effected at the grid of the first amplifier tube. Apart from the method 20 hereinbefore outlined, a number of others based upon purely electrical principles for the production and modulation of the carrier wave are known in the prior art, for instance, the so called mixed tube schemes or the provision of inter- 25 rupters for the photoelectric cell current.

The invention has been illustrated by the accompanying drawing in one of its preferred modifications. By the drawing:

Fig. 1 illustrates the rectification of picture 40 currents according to the prior art;

Fig. 2 illustrates the current curves according to the present invention;

Fig. 3 shows one modification which the system may assume, utilizing a bridge arrangement for 45 selecting currents having a phase displacement of 90° with respect to each other; and,

Fig. 4 illustrates a further modification by which n phases may be obtained through the use of an arrangement of the type shown by Fig. 3.

50 All of these amplification and transmission methods are predicated for their operation and use upon demodulation at the receiving end. A similar process may be needed also for the transition from one transmission system to another system, 55 say, from a cable line to a radio frequency trans-

mitter. In this instance, demodulation is resorted to for the reason that intermediate frequency or double modulation of the radio frequency wave, which in turn becomes the carrier of the picture signals, with the lower carrier frequency usual for amplification and transmission over a cable should be avoided, inasmuch as such double modulation is associated with an undesirable enlargement of the frequency band required for the transmission.

According to former practice, demodulation as hereinbefore set forth was mostly effected by a rectification process. This, however, invariably results only in a pulsating direct current whose enveloping curve represents the shape or the variation of the signals or, in different terms, represents the distribution of brightness in the picture being transmitted.

An illustration of what precedes is illustrated in the drawing (Fig. 1a). The portions of the carrier wave indicated by the dotted line have been cut off by the rectification, the dash line indicates the enveloping curve which corresponds to the brightness variations of the explored picture. Hence, it will be seen that a current curve of this form invariably contains still the carrier frequency, or, under certain conditions (that is, for double rectification or rectification of both halves of the wave) twice the frequency. Double modulation, by which is meant first, modulation at the picture element rate, and second, at the carrier rate, is thus not attained. To smooth the current curve as described, recourse has heretofore been had to the provision of condensers or of a chain system acting as a filter for the said purpose.

Fig. 1b shows the outcome in the case shown in Fig. 1a after the current has passed through a filter chain of ideal action. However, one practical drawback in connection with the use of such smoothing means resides in the time constant, and as a result the shape of the signal as corresponding to the picture is distorted, and this, in turn, for a maximum admissible signal distortion manifests itself in an undesirable reduction of the feasible transmission speed.

Now, the present invention solves the problem of demodulation with the incidental elimination of the carrier wave in the sense as hereinbefore outlined in a fundamentally different manner. According to the method here disclosed the pulsations are suppressed or at least markedly diminished by deriving from the modulated frequency in known manner two or more phase displaced alternating currents; further, each of

these phase displaced alternating currents are separately demodulated or rectified; and, finally, the phase displaced pulsating direct current potentials are combined in some suitable manner.

5 Owing to the ensuing overlapping of the current impulses, a curve characterized by a lower ripple percentage is obtained, the remaining percentage depending upon the number of phases that are produced, in other words, it will be so 10 much smaller, the greater the number of phases. In the simplest case one operates in such a way that two currents roughly in quadrature relation are derived from the modulated carrier frequency, for instance, by that the modulated carrier wave 15 is shorted by an impedance containing a resistance and a capacity in series. In this case, as is well known, the two potentials across the resistance and the capacity are shifted or displaced by an angle of 90 degrees. Each of these 20 potentials, if necessary, after amplification, is rectified separately, and the resultant pulsating direct current potentials, as above pointed out, are combined in a joint consumer (for example, at the grid resistance of a tube or directly at the consumer or load resistance).

25 Fig. 2 may serve to further explain this method: *a* and *b* are the modulated alternating current potentials presenting a phase displacement of 90 degrees and taken off across the terminals of the 30 resistance and of the capacity, respectively, *c* and *d* are the pulsating direct current potentials of double frequency obtained by rectification of both halves, *e* indicates the resultant after combination of *c* and *d*, and the shape of which shows the resemblance with the enveloping of *a* or *b*. Unlike *c* or *d*, the strength of the current no longer drops to zero value, indeed, a curve of a lower 35 ripple percentage is obtained. The fact that in these overtones the carrier frequency is still 40 clearly distinguishable is merely due to the non-sinusoidal shape chosen for the rectified waves *c* and *d* in the drawing. In practice, on the contrary, especially the higher harmonics are far 45 more flattened than has been shown in the drawing. As to the rest, they are readily eliminable as shall later be shown.

50 Instead of the combination comprising a resistance and a capacity as here shown, also any other convenient combination of reactances may be employed for obtaining potentials of any desired 55 number of phases and phase angle. These reactances may preferably be connected bridge-fashion as shown in Fig. 3. The modulated alternating current potential E_o is supplied by way of conductor L_1 L_2 to a bridge comprising the resistances R_1 R_2 and the capacities C_1 C_2 . The

potential E_2 which may then be taken off across one of the diagonals, at points P_1 P_2 , is displaced in its phase with reference to potential E_1 between points P_3 P_4 by an angle of 90 degrees.

80 One practical advantage residing in this circuit arrangement is that the amplitude ratio $E_1:E_2$ no longer is a function of the frequency as would be true in the case where the potentials are taken off at a simple series connection of resistance and capacity. The potentials E_1 and E_2 , if desired, after further amplification, are 85 then utilized for the control of phase displaced modulated alternating current which are rectified each in a distinct system by a "both-half" rectification scheme.

90 The derivation of phase displaced potentials could also be effected by the use of rotary fields by that the alternating current potential to be demodulated is first split in known manner so that a rotating field is obtained, the latter thereupon producing by induction in a system comprising coils conveniently disposed an alternating current of n phases, as shown by Fig. 4. As to the rest, so far as the object of the invention is concerned, fundamentally all such methods 95 known from power work are useful as insure a change from a given number of phases to n many phases.

100 Such remnants or traces of frequencies as remain from the circuit arrangement hereinbefore described and as are to be eliminated by filtering, provided they prove troublesome, can be suppressed by filters. However, contradistinct from the arrangement hereinbefore referred to these filters may be designed that there results a 105 practically far lower time constant. Hence, they occasion no appreciable distortion of the signals to be transmitted and they do not restrict the transmission speed.

110 Although in what precedes, the description of the invention has been applied particularly to the case of picture transmission, it will be understood that the present disclosure is not confined to this application. Indeed, fundamentally speaking, it is useful for all other purposes in the 115 communication arts whenever carrier waves are used for the transmission.

120 Having now described my invention, I claim:

125 The method of demodulating carrier frequencies which comprises, deriving a plurality of phase displaced potentials from the modulated carrier frequency, rectifying the phase displaced carrier potentials, and recombining the separate phase displaced pulsating direct current potentials.
